(57) **CLAIM**

The ornamental design of a box beam level, as shown and described.

DESCRIPTION

FIG. 1 is an isometric view of a box beam level incorporating my new design, wherein the break lines indicate indeterminate length and wherein the portions in phantom form no part of the claimed design;

FIG. 2 is a first side elevation view thereof;

FIG. 3 is a second side elevation view thereof;

FIG. 4 is a top plan view thereof;

FIG. 5 is a bottom plan view thereof;

FIG. 6 is a first end elevation view thereof;

FIG. 7 is a second end elevation view thereof;

FIG. 8 is an isometric view of a first fixed length embodiment of a box beam level incorporating my new design, wherein the portions in phantom form no part of the claimed design, and wherein the end elevation views thereof are identical to the end elevation views illustrated in FIGS. 6 and 7;

FIG. 9 is a first side elevation view thereof, wherein the second side elevation view is a mirror image;

FIG. 10 is a top plan view thereof;

FIG. 11 is a bottom plan view thereof;

FIG. 12 is an isometric view of a second fixed length embodiment of a box beam level incorporating my new design, wherein the portions in phantom form no part of the claimed design, and wherein the end elevation views thereof are identical to the end elevation views illustrated in FIGS. 6 and 7;

FIG. 13 is a first side elevation view thereof, wherein the second side elevation view is a mirror image;

FIG. 14 is a top plan view thereof;

FIG. 15 is a bottom plan view thereof;

FIG. 16 is an isometric view of a third fixed length embodiment of a box beam level incorporating my new design, wherein the portions in phantom form no part of the claimed design, and wherein the end elevation views thereof are identical to the end elevation views illustrated in FIGS. 6 and 7;

FIG. 17 is a first side elevation view thereof, wherein the second side elevation view is a mirror image;

FIG. 18 is a top plan view thereof;

FIG. 19 is a bottom plan view thereof;

FIG. 20 is an isometric view of a fourth fixed length embodiment of a box beam level incorporating my new design, wherein the portions in phantom form no part of the claimed design, and wherein the end elevation views thereof are identical to the end elevation views illustrated in FIGS. 6 and 7;

FIG. 21 is a first side elevation view thereof, wherein the second side elevation view is a mirror image;

FIG. 22 is a top plan view thereof;

(Continued)

FIG. 23 is a bottom plan view thereof;
 FIG. 24 is an isometric view of a fifth fixed length embodiment of a box beam level incorporating my new design, wherein the portions in phantom form no part of the claimed design, and wherein the end elevation views thereof are identical to the end elevation views illustrated in FIGS. 6 and 7;
 FIG. 25 is a first side elevation view thereof, wherein the second side elevation view is a mirror image;
 FIG. 26 is a top plan view thereof; and,
 FIG. 27 is a bottom plan view thereof.
